UNITED STATES PATENT OFFICE.

JOHN E. FUNK, OF STOCKTON, CALIFORNIA.

DREDGER-BUCKET MOUNTING AND OPERATING STRUCTURE.

Application filed February 8, 1927. Serial No. 166,680.

This invention relates to improvements in dredging apparatus, either of the floating or land supported type which utilizes a bucket of the opposed grab or clam shell type, supported from a boom, with a cable for closing the grabs. Such buckets are all constructed on the same general principle and include opposed jaws or grabs pivoted together for opening and closing movement. There are various mechanisms in common use mounted in connection with the buckets for applying the closing movement of the jaws with a pull on the operating cable. As far as I am aware, however, such pull, no matter what the type of associated bucket mechanism may be, always tends to pull up on the bucket simultaneously with the closing of the jaws. The result is that under certain conditions, especially when attempting to operate in hard ground, the jaws will be closed without appreciably digging into the ground and the bucket will be raised with at best only a partial load.

This defective feature is recognized by manufacturers and attempts to overcome the raising tendency of the bucket have been made in various ways. One such method consists in making the bucket very heavy so that the weight of the bucket itself is sometimes greatly in excess of that of even a capacity load. These extra heavy buckets however not only fail to overcome the defect but of course add considerably to the dead weight which must be continuously supported and manipulated during the operations of the dredger. Considerable power is therefore used to no useful end and dredging operations are slow, uncertain and expensive.

Other methods of overcoming the defect have also been tried, such as using a number of sheaves over which the operating cable passes, to provide leverage and power to close the grabs and overcome the lifting tendency. This arrangement does not altogether overcome the defect, and the length of cable necessarily pulled in when closing the bucket consumes considerable time in the aggregate. It may therefore be accepted as a fact that as long as the bucket is free to move upwardly (and the buckets are all now suspended from one or more cables), such methods cannot be entirely successful.

The principal object of my invention therefore is to support the bucket from the

boom in such a manner that the bucket closing cable can never exert any upward pull on the bucket no matter how hard the dirt in contact with the bucket may be. As a result the bucket can successfully dig in dirt which ordinary buckets will not appreciably penetrate. The supporting means for the bucket is also of such a nature that not only is the cable prevented from acting to raise the bucket but the latter may be positively pressed against the ground by its own weight and that of the supporting boom as well. This is obviously a valuable aid in causing the bucket to penetrate into the dirt.

A further object of the invention is to arrange the bucket operating cable in connection with the other features of the apparatus in such a manner that the closing pull on the cable definitely exerts a downward pull on the bucket. This arrangement of course renders it possible for the bucket to penetrate dirt of practically any character, since the greater the pulling pressure on the cable the greater will be the downward pressure exerted on the bucket. As a result of this combination of features the bucket may be much lighter than is at present possible without interfering with its carrying capacity or with its efficiency of operation. The power consumed in dredging operations is materially lessened, and time and money is saved, since a fully loaded bucket is practically insured with every manipulation and closing of the same.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of one form of my improved bucket and boom operating cable as arranged to exert a definite downward pull on the boom.

Fig. 2 is a side elevation of the same form of bucket and boom arrangement, the bucket operating cable extending directly along the boom to the bucket.

Fig. 3 is a side elevation of another form

of bucket and boom arrangement utilizing an auxiliary boom from which the bucket is suspended, in addition to the main boom.

Fig. 4 is a similar view of the same mounting arrangement as shown in Fig. 3 but with the bucket operating cable arranged to exert a definite downward pull on the auxiliary boom.

Fig. 5 is a fragmentary cross section on the line 5—5 of Fig. 1.

Referring now more particularly to the characters of reference on the drawings, the supporting structure of the dredger may, as indicated in the preamble, be either of the land or water borne type. In the present instance I have shown such structure as being the same as that shown and described in my co-pending application on a dredger frame structure, filed January 24th, 1927, Serial No. 163,251. Such structure comprises essentially a main frame 1 supported on its forward end on an endless track truck 2. Turnable on the main frame at its forward end is a turntable 3 on which is mounted a mast 4 pivotally supported at its upper end by a brace structure 1^a extending rearwardly and downwardly to the main frame. This structure is common to all the arrangements illustrated in the drawings.

Referring particularly for the present to Figs. 1 and 2, a boom 5 of suitable length is pivoted on the mast at its base, said boom being supported at its upper and outer ends for vertical adjustment by means of a cable 30 and sheave arrangement of suitable character, indicated generally at 6. This arrangement extends between the boom and the top of the mast, its operating cable 7 extending thence to a drum on the main frame over guide sheaves 8 mounted in connection with the mast and preferably arranged as called for in the co-pending application above mentioned.

Pivottally mounted on and depending from the outer end of the boom is a rigid bucket supporting structure S. In Figs. 1 and 2 this structure S is shown as being of telescopic or extensible form and comprises a pair of tubular members 10 and 11 slidably and turnably fitted within each other, the male member being uppermost. The outer or female member 11 has a long slit 12 so that said member may be frictionally engaged with the member 10 by suitable clamps 13. A thrust collar 14 is preferably clamped on the member 10 directly above the member 11, the latter having one or more hooks 15 or the like projecting upwardly to overhang and engage the thrust collar. If it is desired to extend or contract this structure all the clamp members are loosened so as to allow the member 11 to slip on the member 10. If it is merely desired to turn the bucket (hereinafter described and which is supported from the member 11) so as to alter the set-

ting of said bucket relative to the boom, the clamps 13 are loosened but the collar 14 is left tight. The member 11 will therefore be held from dropping by the hooks 15 so that it can be rotated to any desired position, when the clamps 13 are again cinched up so as to hold the member 11 immovable and to take some of the strain off the hooks and collar 14.

Depending from the lower end of either type of supporting structure S is the bucket B. The bucket may be of any standard grab or clam-shell character, and in the present instance is shown as comprising opposed grabs 16 having short arms 17 projecting toward each other from their upper and adjacent ends and pivoted together. Rigid and nonbuckling arms 18 are pivoted onto the grabs at their opposite ends and converge thence upwardly to a common pivotal connection with the lower end of the supporting structure S. These grabs as usual tend to open out by their own weight and are closed by an upward pull applied to the outer end of an arm 19 mounted in connection with one of the grabs and projecting past the pivotal connection of the arms 17 into or toward the other grab. One end of the supporting cable 20 is attached to the outer end of this arm, extends around a sheave 21 mounted in connection with the arms 18 at their upper ends, thence up alongside, between or through the supporting structure S (depending upon which type is used) to and over a sheave 22 mounted on the boom 100 rearwardly of but adjacent the connection of the structure S therewith.

In the arrangement shown in Fig. 2 this cable 20 then extends continuously the full length of the boom to and around sheaves 23 mounted on the mast in the same manner as the sheaves 8 to the control drum on the frame. It will therefore be seen that with this arrangement a closing pull on the cable is transmitted to the bucket arm 19 without any tendency or possibility of lifting the bucket, owing to the rigid structure S and the rigid arms 18 disposed between the boom and the grabs. If the boom supporting cable 7 is left slack when the bucket is engaged with the dirt, the weight of the boom and bucket will serve to press the latter into the dirt.

In the arrangement of the cable 20 in Fig. 1, after leaving the sheave 22, said cable extends lengthwise of the boom to a point below the same and then around a sheave 24 mounted in a fixed position relative to the boom below the same and secured to the turntable and the mast by suitable rigid connections as at 25. The cable then extends into and around another sheave 26 mounted on the boom forwardly of the location of the sheave 24; thence back to and around the sheave 24, to and around the sheave 26, and

thence to the mast sheaves 23. By means of this arrangement the pull on the cable will not only act to pull up on the arm 19 and close the grabs, but will at the same time exert a powerful downward pull on the boom, owing particularly to the relatively low and fixed sheave 24 over which this cable passes before passing about the sheave 22. It will be noted that the sheave 24 is the most important element of this arrangement, and the number of turns of the cable about the sheaves 24 and 26, and the particular direction in which the cable runs from the sheave 22 to the sheave 24, may be altered as may be desired, or necessary to suit different structures and conditions. When the bucket is closed it is lifted by raising the boom, the cable 20 being kept under tension during this operation by proper manipulation of the drum over which the cable is wound.

In the arrangement shown in Figs. 3 and 4, the main boom 5^a is fixed onto the mast instead of being pivoted, and the supporting structure 6^a between the mast and the boom at the top is non-adjustable, except possibly sufficient to enable any stretch to be taken up. Pivotaly connected to the main boom near its base and extending thence forwardly and under the same, is an auxiliary boom 27. This auxiliary boom comprises a pair of transversely spaced members disposed outside of the boom 5^a so as to be relatively wide and hence capable of being easily made of a transversely stiff and rigid nature. The supporting structure S (of the type either as shown in Figs. 1 or 2), and the bucket B of the same type as previously described, or any other suitable form, depend from the outer end of the boom 27. This boom is supported at its outer end and raised or lowered when necessary to raise and lower the bucket by a supporting and control cable 28 applied thereto. This cable extends upwardly and around a sheave 29 mounted on the boom 5^a and thence to and around a sheave arrangement 30 mounted on the mast and corresponding in arrangement to the sheaves 8 etc.

In the arrangement shown in Fig. 3 the closing cable 31 for the bucket extends around a sheave 32 mounted on the boom 27 and thence along the boom to and around sheaves 33 mounted on the mast. At the rear or pivoted end of the boom 27 this cable preferably passes between vertically spaced sheaves or rollers 34 so as to maintain the cable longitudinally alined with the boom regardless of the raising or lowering of the latter.

In the arrangement shown in Fig. 4 the bucket operating cable 31^a after passing about the sheave 32 extends lengthwise of the boom 27 to a point below the same adjacent its rear pivoted end, where it passes

about a sheave 35 fixed relative to said boom and supported from the main boom and the mast by suitable rigid connections 36. The cable then passes upwardly to and about the sheaves 33. Though I have shown in this instance the cable as having a single run from the sheave 32 to the sheaves 35, it will be obvious that the same multi-run cable arrangement may be provided as shown and described in connection with Fig. 1 and vice versa. The end attained is the same, namely—the exertion of a positive down pull on the bucket when the bucket operating cable is pulled to close the grabs. When thus functioning the boom controlling cable 28 should be staked off so as to allow the boom 27 to be pulled down, in addition to allowing its own weight to aid in this operation. If the use of this lever and power increasing cable arrangement is not desired or necessary in certain cases the bucket operating cable may be simply withdrawn from engagement with the sheave 35 and allowed to run straight from the sheaves 33 to the sheave 32.

It is to be distinctly understood that while I have shown and described a special form of mast and main supporting structure for the boom, and a special form of bucket, these features in themselves are capable of being altered to any desired extent without interfering in the slightest with the operation and functioning of the important features of my invention. In other words, a bucket and boom supporting arrangement may be mounted in connection with the boom supporting structure of any dredger; and any bucket as long as it is of the general type defined may be supported from the rigid structure depending from the boom.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In a dredger, a boom, a bucket therebelow, said bucket comprising opposed grabs pivoted together for opening and closing movement, rigid connection means between the boom and bucket and supporting the latter in suspended and definitely spaced relation to the boom, means for closing the grabs including a cable to be pulled, and connections between the cable and boom for causing such pull to exert a positive downward pressure on the boom and bucket.
2. In a dredger, a boom, a bucket there-

below, said bucket comprising opposed grabs pivoted together for opening and closing movement, rigid connection means between the boom and bucket and supporting the latter in suspended and definitely spaced relation to the boom, means for closing the grabs, and means functioning in conjunction with the operation of said closing means for exerting a positive downward pressure on the bucket.

3. In a dredger, a boom, a bucket therebelow, said bucket comprising opposed grabs pivoted together for opening and closing movement, rigid connection means between the boom and bucket and supporting the latter in suspended and definitely spaced relation to the boom, means for closing the grabs including a cable to be pulled, and means supporting the cable in a manner to cause such pull to exert a positive downward pressure on the bucket.

4. In a dredger, a boom, a bucket therebelow, said bucket comprising opposed grabs pivoted together for opening and closing movement, rigid connection means between the boom and bucket and supporting the latter in suspended and definitely spaced relation to the boom, means for closing the grabs, and means applied to the boom and operable simultaneously with the closing of the grabs for exerting a positive downward pressure on the bucket under all conditions and positions of the latter.

5. In a dredger, a boom pivotally supported at one end, means for raising and lowering the boom about its pivot, a bucket below the outer end of the boom, said bucket comprising opposed grabs pivoted together for opening and closing movement and rigid arms projecting upwardly from opposed connections with the grabs, rigid vertical connection means between the boom and the upper ends of the arms, a sheave mounted on the boom in substantial vertical alignment with said connection means, a second sheave mounted on the boom rearwardly of the first named sheave, a third sheave disposed below and fixed relative to the boom, and a grab closing cable extending from rearwardly of the second sheave around the same, then to and around the third sheave, and thence to and around the first sheave and down to the bucket.

6. In a dredger, a boom pivotally supported at one end, means for raising and lowering the boom about its pivot, a bucket below the outer end of the boom, said bucket comprising opposed grabs pivoted together for opening and closing movement and rigid arms projecting upwardly from opposed connections with the grabs, rigid and definitely spaced vertical connection means between the boom and the upper ends of the arms, a sheave mounted in the boom in substantial vertical alignment with said

connection means, a second sheave disposed below and ahead of the rear end of the boom and fixed relative thereto, and a grab-closing pull cable extending downwardly around the second sheave, thence to and around the first sheave and down to the bucket.

7. In a dredger, a boom, a bucket therebelow, said bucket comprising opposed grabs pivoted together for opening and closing movement, rigid connection means between the boom and bucket and supporting the latter in suspended and definitely spaced relation to the boom, means for closing the grabs including a cable projecting upwardly from the bucket to the boom, a sheave on the boom about which the cable passes, said cable then extending lengthwise of the boom to a point below and in front of the rear end of the same, and a sheave fixed relative to the boom about which the cable passes at its lowest point.

8. In a dredger, a boom, a bucket therebelow, said bucket comprising opposed grabs pivoted together for opening and closing movement, rigid connection means between the boom and bucket and supporting the latter in suspended and definitely spaced relation to the boom, a sheave on the boom adjacent the connection of the bucket supporting means therewith, and means for closing the grabs including a cable to be pulled extending from the bucket to and around the sheave and then downwardly relatively to the boom.

9. In a dredger, a boom, a bucket therebelow, a rigid circular member secured to and depending from the boom, a sleeve secured to and projecting upwardly from the bucket and turnably and slidably associated with the circular member, and clamping means for holding the sleeve in any desired position on the circular member while the dredger is in operation.

10. In a dredger, a boom, a bucket therebelow, means for supporting the bucket from the boom comprising extensible male and female members, turnably and slidably mounted together, means for clamping said members to prevent relative movement thereof, and means between the members for permitting turning movement of the one on the other when the clamping means is loosened while preventing longitudinal movement of the members relative to each other.

11. A structure as in claim 10, in which said last named means comprise a collar releasably fixed on the male member outwardly of the female member, and elements on the female member engaging the collar in a manner to cause the latter to support the female member and permit of relative rotation of the members.

In testimony whereof I affix my signature.
JOHN E. FUNK.
